Application June 30, 1947, Serial No. 758,022

9 Claims. (Cl. 122—356)

1

This invention relates to heating, and more particularly to a method and apparatus for heating fluent material as it is passing through a conduit.

The invention is particularly concerned with the provision of the necessary or required amount of heat appropriate to the particular use for which it is employed and to the control of such heat generally and in localized areas to a degree heretofore unattainable for producing a desired heating effect, thus controlling within very small limits the overall temperature and the temperature in different specific localities or zones throughout the area heated.

This application is a continuation-in-part of my co-pending application Serial Number 326,617, filed March 29, 1940, now abandoned.

In many modern processes, it is necessary that the material in various portions of a conduit be accurately heated to different temperatures, and that these temperatures be rapidly and accurately changed from time to time. With long-flame burners and large wall surfaces that are ordinarily used it is impossible to obtain localized temperature control along various portions of the conduit or to obtain rapid changes in temperature.

When using a long or torch type flame, if the axis of the flame is parallel to an object to be heated, as for instance the tube bank in a still, the heating effect upon this object cannot be uniform along the length of the flame, regardless of the volume of gas burned. Varying the flame length will merely move the relatively hot and cold portions of the flame longitudinally of its axis and along the object heated. If, on the other hand, the axis of the flame is at right angles to the object to be heated, varying the flame length may move the hottest portion of the flame toward the object and might actually touch it, or may go beyond it in which case the object would be actually at a lower temperature on account of being within the cooler portion of the flame.

In an attempt to off-set this effect of long flames and to obtain good heat distribution throughout the furnace chamber, it is customary to use a very large amount of excess air in conjunction with a rich flame. This practice, besides failing to accomplish the desired heating, adds a fire hazard in the furnace. It is so happens that combustible material is passing through the conduit and a fracture thereof occurs the material will escape in the presence of flame and excess air sufficient to support combustion. This excess air tends to oxidize the tubes excessively, thus adding to the cost of maintenance.

In some cases long flames have been used to heat large wall areas in order that heat could be radiated therefrom to the conduit. This attempt

5 to utilize the beneficial effects of radiant heat has met with little success because there has been no way to control its utilization in individual zones. The large heated wall has caused each portion of the conduit to be heated substantially to the same temperature. This is true even though the angle at which the flame impinges upon the wall may be varied and even though the length of the flame may be varied. It is noted that long flames and large volumes of combustion air go hand in hand whether the flames are used to heat the conduit directly or indirectly through heating the furnace walls.

As stated above, rapid change of temperature is necessary in order to control the refined, high temperature processes in use today. This cannot be done where large wall surfaces are heated or where large amounts of combustion air are used because of the thermal lag. So much heat is stored in the furnace walls and in the products of combustion and excess air within the furnace chamber that a rapid increase or decrease of temperature cannot be obtained.

From the above it will be seen that to obtain accurate zone control of the heating of fluid in a conduit several things are necessary among which the following are noted. The excess air and the large volumes of air and gas used to obtain convection heating must be eliminated. Radiant heat in controllable form must be applied to the conduit rather than that obtained by the haphazard manipulation or directional change of burners. The heat source for effective zone control must be close to the heated object.

35 In order to overcome the above-mentioned deficiencies in prior types of heating equipment it has been found in accordance with the present invention that the desired results may be obtained by utilizing a number of accurately positioned and regulatable sources of radiant heat for producing the required heating effect. Since the heat rays from a radiant heat source travel in straight lines, and can be directed by the configuration of the heat source, the distribution of such radiated heat may be directed over any desired area. Also by utilizing a plurality of such sources in which the heated areas overlap, accurate and close control of the heat in any given area may be obtained by simple adjustment of 40 the fuel input to the radiant burners.

With radiant heating it is also possible to design heating devices with the heat source located close to the heated areas without the danger of flame impingement or highly localized heating, since with this type of heat source no actual flame extends beyond the confines of the burner. The temperature can thus be critically controlled while still maintaining maximum burner efficiency and resulting fuel economy at 45 any given adjustment thereof.

It will therefore be apparent that among the objects of the invention is to provide a method of and apparatus for heating fluent streams simply, efficiently, economically and continuously, with flexible control susceptible of critical adjustment of temperatures within desired heating areas or zones.

A specific object of the invention is to provide an improved method of and apparatus for heating fluent material flowing through a bank of tubes, by means of gas burners of such character and so disposed that a large portion of the heat liberated in their operation is radiated to the tubes, from the burning gases and from incandescent refractory portions of the gas burners, without subjecting the tubes to flame impingement.

Another specific object of the invention is to provide a method of and means for heating fluent material in tubes largely by radiation from gas burners, in which the rate of heat transmission to the tubes and material therein is relatively high and in which the relative amounts of heat transmitted to different portions of the tubes is subject to close control.

Another object of the invention is to provide heating equipment with sufficient delicacy of control that its use is greatly enlarged, in that it can be employed with materials requiring close temperature regulation so that injury thereto can be avoided. This includes the use of brittle substances such as quartz and other materials as the conduit through which the material to be heated passes. By the use of such materials for conduits new processes requiring temperatures above the range to which metal tubes can be subjected and the heating of highly corrosive materials may be accomplished.

A further object of the invention is to provide heating apparatus in which the heat is radiated from surfaces having such configuration and relative location that the heat will be uniformly distributed over a predetermined area and in which the control of the radiant heat source will accurately control the temperature in the area receiving the heat.

A further object of the invention is to provide heating equipment and a method of heating capable of both localized and properly distributed heating, and in which the temperature in any selected area or zone can be accurately controlled over the total temperature range, in order to obtain desired temperatures within the heated area, whether such temperatures be 200° F., 2000° F., or any other desired temperature or temperatures.

Another object of the invention is to provide a process of heating in which accurate control of the heat input in selected zones or areas can be obtained, and in which the heat input in such zones may be reduced to zero or therebelow by the introduction of cooling effects in these zones while maintaining the desired heating effect in closely adjacent or other zones.

Another object of the invention is to provide heating apparatus in which all parts are accessible for inspection and in which the heating means can be shut off and air introduced therethrough to effect uniform cooling of the entire furnace or any portion thereof for repair, inspection, or other purpose.

Another object of the invention is to provide a process of heating applicable to the treatment of fluent materials in which reactions may occur rendering necessary the accurate control of heat input at any given point in the travel of the ma-

terial thereof, and also may require reducing such heat input to the extent of cooling when the reaction of the material heated makes it desirable.

Still another object of the invention is to provide a heating apparatus and process adaptable for use in treating fluent materials continuously, and in which the heat necessary for such treatment varies in accordance with different characteristics of the material during the heating process, and to apply the required heat in different areas or zones during the continuous movement of the material and the changes which occur therein.

The invention is thus well adapted for use in known processes including superheating of steam, heating an organic fluid to a high temperature, oil cracking, or the like, as the material flows continuously in an elongated flowpath, to effect changes in the chemical composition of the fluid which require, or make desirable for optimum results, different rates of heat transmission to the fluid passing through different portions of said path.

In a fluid heater constructed in accordance with the present invention, there is no risk of injurious flame impingement against the tubes, and with burners suitably distributed in the furnace chamber, heat may be transmitted at a relatively high rate to tubes separated only a foot or so from said wall, and with such regulation of heat distribution as to avoid risk of local overheating of any tube or tube portion. The use in a fluid heater of the multiplicity of burners characteristic of the present invention, permits any control or regulation of the heat distribution which may be practically desirable, to be effected by suitable regulation of the rate of fuel supply to the different burners.

Furthermore, the character of the burner employed and the fact that the radiation is directly from the burner combustion space through the open side of the latter, permit of a high radiation temperature and higher rate of heat radiation in a heater for fluent material constructed in accordance with the present invention, than are practically possible of attainment in known types of heaters having a heat conducting and radiating wall of carborundum or of a refractory metallic alloy between a combustion or heating gas space and a space including tubes containing fluent material to be heated. As is well known, the rate of heat transfer by radiation from a high temperature source of heat to a colder body to be heated is proportional to the difference between the fourth powers of the absolute temperatures of the source and body.

Further objects and advantages of the invention will be apparent from the following description taken in conjunction with the accompanying drawings, wherein:

Fig. 1 is a perspective of a heating apparatus constructed in accordance with the present invention and with parts broken away for greater clarity;

Fig. 2 is a section on the line 2—2 of Fig. 3 and showing the internal structure of a modified form of heating apparatus;

Fig. 3, a side elevation on the line 3—3 of Fig. 2;

Fig. 4, a fragmentary diagrammatic view showing how a cooling medium may be introduced to the burners;

Fig. 5, a fragmentary perspective of a different type of heat radiating wall for use with the furnace;

Fig. 6, a section of another form of heating apparatus constructed in accordance with this invention;

Fig. 7, a top plan view partially in section of the apparatus shown in Fig. 6, and

Fig. 8, a detail section of one type of short flame burner which may be advantageously used in the structure illustrated in Fig. 5.

With reference to the drawings, there is shown in Fig. 1 one form of heating apparatus for the heat treatment of fluent materials and this apparatus is particularly adapted for maintaining a close regulation of the temperatures to which the fluent material is subjected as it travels along a predetermined path.

The apparatus comprises an enclosure having outer walls 10 defining a heating chamber 11 and having tubes or pipes 12 forming a tube bank located centrally within said chamber 11. These tubes receive the fluent material to be heated and define a serpentine path through which the material flows. To this end tubes extend horizontally in the furnace chamber and alternate tubes are connected by return bends so that the fluid moves back and forth along the length of the furnace as it travels from the top to the bottom thereof. The tubes are staggered with respect to each other so that they in effect form two vertical rows that are offset so that each tube may receive radiation around its entire circumference directly from the furnace walls.

The inner wall 13 of the chamber 11 is composed of refractory material of a character to withstand the heat to which it may be subjected in any particular installation. Chamber 11 is substantially closed except for passage 14 at its top which forms an exhaust outlet for the products of combustion from the heating chamber. Also located within the passage 14 may be tubes 15 communicating with tubes 12 to provide for the preheating of the material flowing through the tubes, thus utilizing any waste heat that may pass through the exhaust passage 14.

A plurality of radiant burners 16 are located in the opposed side walls of the chamber 11 and these burners are arranged in such a manner that radiant heat therefrom is distributed uniformly over the tubes 12 forming the tube bank. The burners in effect form a radiant wall of the furnace.

The burners 16 may be supplied with gas or other combustible material through headers or manifolds 17 and individual pipes 18 leading to each burner. A valve 19 is also provided in each of the individual pipes 18 in order that the supply of gas to each burner may be selectively controlled.

Each of the headers or manifolds 17 is supplied with the gas and air mixture through an automatic control valve 65 that is adjusted in accordance with the temperature of the furnace adjacent that part thereof which is heated by the burners supplied from a given manifold. For this purpose thermo-couples 66 are inserted through suitable openings in the furnace walls at various points. These thermo-couples are connected in known manner to suitable recording and controlling instruments used to adjust the valves 65 in accordance with the thermocouple temperature. Normally the thermocouples along a single horizontal plane heated by the burners supplied by a single manifold are connected to the instrument for controlling the supply of gas and air to that manifold. The pipes in which valves 65 are located are each provided with a

by-pass having a manually operated valve 67 therein. This permits manual regulation of the furnace temperature whenever desirable or necessary. Such regulation is made in accordance with the temperature as indicated by the thermocouples.

10 A metal casing 20 surrounds the outer wall 10 forming the chamber 11 and the complete structure is supported on legs 21. There is also provided a platform 22 having a railing 23 for the use of the operator who may adjust or inspect the individual burners.

15 In the operation of the device shown in Fig. 1 and described above, it is necessary that the burners 16 located in the walls of the furnace be of radiant type as distinguished from a burner of the long flame or torch type. The particular burner disclosed in Figure 1 need not be described in detail as any radiant burner may be used as is indicated below. The burner shown is that which forms the subject matter of my prior Patent No. 2,215,079. A burner of this type is supplied with gas and air under pressure, the combustible mixture being completely burned in a combustion cavity 16a of the burner with the gases of combustion passing through the furnace chamber and out through the opening or passage 14 in the top. As explained in detail in that patent, the hot gases of combustion heat the wall defining the cavity of the burner to incandescence so that heat is radiated from this burner to the tubes directly in front thereof.

20 As will be observed from an inspection of Fig. 1, there are a large number of these radiant heat burners distributed over the opposed side walls of the furnace, and the combustion spaces and the arrangement of the burners with regard to the tube bank and to each other is such that the areas heated by these burners overlap sufficiently to avoid cold spots between adjacent burners. The overlapping of the heating is necessary in this particular application in order to obtain accurate zone control of the heat supplied to the tube bank throughout the length thereof.

25 The present invention contemplates the proper number and arrangement of radiant heat sources to provide for the continuous heating of the complete tube bank and to maintain a close and accurate zone control of temperatures at all portions thereof. With the appropriate number, arrangement, and character of burners, the desired temperatures in the several zones can be controlled by controlling the amount of fuel supplied to each burner in accordance with the temperature of that zone. As the flame does not extend beyond the confines of the burner and consequently does not impinge upon the tube bank, the desired effective heat is supplied to the tube bank largely by radiation. Consequently, the heat supplied by each burner to its corresponding area may be accurately controlled by controlling the supply of fuel to the burner. The hot products of combustion from the burners in the furnace chamber of course add some heat to the tubes, but the amount of this heat is too inconsequential to prevent accurate zone control.

30 The present invention is particularly applicable to processes in which it is necessary to supply relatively large amounts of heat over certain portions of the travel of fluid material through the tube bank and then to cool or hold it at a desired temperature level for a further portion of the travel of the material before being subjected to a different temperature.

Cooling of certain portions of the tube bank after heating may be easily accomplished with the present apparatus by the introduction of cold air through the burners in desired selected locations. One means for accomplishing this is shown in Figure 4 in which the gas and air supplied to a manifold 17 from control valve 65 passes through a three way valve 68, the other or third branch of the valve leading to a pipe 69 through which air may be supplied to the burners. In the normal operation of the system, the three-way valve 68 will be adjusted so that the air and gas mixture passes through the valves 65 and 68 to the manifold 17. When, however, it is desired to reduce the temperature of that portion of the furnace which is heated by the burners supplied by the manifold 17, the three-way valve 68 is adjusted so that air can pass through the manifold 17 and through the burners to cool those tubes which are normally heated by these burners. A similar arrangement can be provided to supply cooling air to each burner individually, if desired. Cooling air to each burner can be introduced through all of the burners in order to rapidly cool the furnace in case this may be necessary.

Tubes 12 of the tube bank may be of material appropriate for the particular use to which the tube bank is placed, for example, stainless steel or other appropriate metal may be used in certain processes, although the invention contemplates and is particularly adapted for the use of other materials, such as quartz or the like because of its high resistance to chemical reaction and the high temperature to which it can be heated. It has not been previously commercially feasible to employ quartz tubes and other substances which were subjected to high temperatures because of brittleness or other characteristics which would not withstand uneven stresses caused by uneven heating of the furnace itself. The close temperature control possible with the present invention makes it possible to maintain a temperature control within plus or minus 5° F., although in normal applications the control of temperature within 1% is all that is necessary. This accurate control is entirely possible and practical over a range from approximately 200° F. to 2000° F. Such accurate zone control of temperature can only be obtained where the heat is supplied from a radiant source because if there were any appreciable convection heating, there would be no adequate control over the heating effect produced by the convection currents and consequently no accurate zone control for the total heating effect.

An added advantage of the structure described above resides in the fact that when it is necessary to shut down the apparatus, for cleaning, repair or the like, it is only necessary to introduce cold air through all of the burners in order to obtain a relatively quick cooling of the complete structure, it being possible by this method to cool the structure sufficiently for workmen to enter to make repairs within a matter of 15 or 20 minutes, whereas in conventional structures, two or three days were often required for the necessary cooling.

While for many applications, the burners of the type shown in Fig. 1 of the drawing and described in my prior Patent No. 2,215,079 are provided, other types of radiant burners, as mentioned above, may also be used. For example, a furnace wall may be made of a plurality of burners of the type shown in Fig. 5 of the drawing. In this

figure there is a furnace wall formed of a series of compartments, each of which has a floor 71 through which extends a burner 72 of a type disclosed in Patent No. 2,287,245. This type of burner has a comparatively short flame which may be readily controlled. This flame impinges upon a sloping wall 73 that lies directly above the floor 71 of each compartment. These sloping walls are heated to incandescence by the flame within the compartment in which complete combustion occurs. Each compartment wall radiates heat to the tubes in front of the same, the interior furnace wall as a whole being composed of a series of similar compartments so that all portions of the tubes in the furnace are heated by radiant heat projected from the sloping walls 73. The walls themselves are composed of a series of refractory blocks so shaped that the various compartments are produced by properly laying the blocks in relation to each other. The compartments are separated from each other by partitions 74, also of suitable refractory material. As shown in the drawing, the various compartments are symmetrical with one compartment directly above the other. The compartments may be arranged in any desired manner although at times it may be desirable to arrange them so that one row of compartments is staggered with respect to the adjacent row, as shown in Fig. 1. This prevents any possibility of a cold spot in the tube for containing the material to be heated because of the location of partitions 74.

Each of the burners used with a furnace wall of this type is supplied individually through a pipe 75, the flow through which is controlled by a manually adjustable valve 76. These pipes 75 are connected to manifolds 77 located along the outer walls of the furnace in a manner similar to that of the manifolds 17. As in Fig. 1, it is generally desirable to have all of the compartments in a single horizontal row or in adjacent rows serviced by the same manifold so that as the intensity of the gas flame is changed in one row of compartments the heat projected by the radiant walls in a single horizontal plane can be changed. In this way the tubes extending horizontally at different levels in the furnace chamber can be heated to different temperatures and zone control thereby obtained. Provision may be made for supplying cooling air as indicated in Fig. 4.

There is shown in Fig. 8 the details of a short flame burner 72 which may be used in the structure of Fig. 5. While this particular burner may be advantageously employed, it is to be understood that any suitable short flame type burner may be used in this application, as it is only necessary that the burner heat the wall portion 73 and that complete combustion take place within the space 71.

From the foregoing it will be readily apparent that the fluent material to be heat treated is introduced into the tubes 12 adjacent the upper end of the tube bank and flows through the preheating portion 15 of the passage 14. This preheats the fluent material to a temperature somewhat below that at which it is desired to treat the material, but utilizes the heat which would otherwise pass out of the furnace and be wasted. As the material to be treated passes into the tubes within the furnace chamber 11, it is subjected to the desired heat controlled by the particular burners heating that particular area of the tube bank, it being necessary in various processes of treating streams of fluent materials to vary the

heat input thereto at frequent intervals throughout the cycle.

The burners may be individually adjusted to provide the desired heat input at any location in the travel of the material through the tube 12 in accordance with the heat treating process being followed. As indicated above, if it is desirable because of an exothermic reaction in the material, or for other reason, to cool said material, cold air may be admitted through the appropriate burner or burners in order to maintain the desired temperature. As the material passes from this region additional heat may be supplied by other burners in order to complete the process. By utilizing radiant type burners as described above to obtain a radiant wall, there will be no flame impingement on the tubes forming the tube bank and therefore no localized over-heating resulting in the formation of coke or other deposits within the tubes.

There is a further advantage in utilizing this type of burner in that no excess air is required since complete combustion takes place within the burner combustion space and consequently there is insufficient oxygen within the furnace chamber 11 to support combustion therein. When combustible material is flowing through the tube bank and a rupture occurs, there is little danger of fire as the oxygen in the chamber is insufficient to support combustion. The small volume of heated gas in the furnace chamber increases the speed and accuracy of control.

A modified form of the invention is illustrated in Figures 2 and 3 in which a furnace is provided having an outer shell 42 and a lining 43 of refractory material defining a furnace chamber 44, openings 45 being provided in the top of the chamber 44 to permit escape of the products of combustion. Mounted in the opposing side walls of the chamber are a plurality of burners 46, which may be of the radiant type described above or which may be of any other desired type which provides a purely radiant heat source.

A tube bank 47 is disposed within the chamber in a vertical arrangement and defines a serpentine path for the material treated in order to permit exposure of the maximum external surface area of the tubes to the heat emanating from the radiant burners. This tube bank differs from that shown in Fig. 1 in that the tubes are so arranged that they form, in effect, three vertical rows instead of the two rows as disclosed in that figure. The tube arrangement is the same as that of Fig. 1 to the extent that the tubes are so positioned vertically that each tube can receive radiation directly from both furnace walls. This insures that the tube passes or lengths will be evenly heated around their circumferences. As in the embodiment of Fig. 1, fuel for the burners may be supplied through headers 48, controlled by valves 49, each burner being fed from a pipe 50 tapped into the adjacent header and controlled by the valve 51.

Although the tube bank in Fig. 2 is shown as broken in the center, it is to be understood that this part is omitted in order that the arrangement of the burners in the side walls may be clearly seen whereas in fact the tube comprising the bank is continuous from its inlet 52 to its outlet 53. The burners in this embodiment, as in that of Fig. 1, are so placed and adjusted that the desired heat input may be obtained at any point along the path of travel of the material under heat treatment. Suitable openings are pro-

vided in the furnace wall as shown at 46a through which thermocouples responsive to furnace temperature may extend.

The operation of the furnace disclosed in Figs. 2 and 3 is very similar to that disclosed in Fig. 1, in that fluent material is admitted to the inlet 52 and passes progressively through the furnace, the heat supplied thereto being controlled by each burner in the zone served thereby and resulting in accurate control of the temperature of the fluent material being treated at any position or zone in the travel thereof through the tube bank. In this case, also, the various valves 54 may be manually adjusted if it is desired to adjust manually the temperatures of the various zones of the furnace.

In Figs. 6 and 7 there is shown a further modified form of the invention in which the furnace is substantially circular in cross-section and in 20 which the tube bank is vertically arranged with both the inlet and the outlet thereto at the top of the furnace. The furnace as shown in Fig. 6 comprises an outer casing 54, an inner wall structure 55 of refractory material, and a plurality of radiant burners 56 arranged in a spiral pattern from the bottom to the top of the furnace in the side wall structure thereof. Centrally of the furnace, there is provided a structure 57 of refractory material which supports the tube bank 58 which is a continuous tube arranged in a plurality of vertical loops located about the circumference of the central refractory structure 57, the tube bank having an inlet 59 and an outlet 59a.

35 The top of the furnace is closed by a cap or cover 60 of refractory material and with an outer casing 61. The cap 60 is removably positioned on the top of the cylindrical outer portion of the furnace in order to permit removal of the inner refractory structure 57 and the tube bank 58 for cleaning, or repairs or other purpose. The casing 61 is provided with an opening 61a through which the products of combustion may pass.

40 As in the other forms of the invention, material passes through the tube of this furnace and is subjected to controlled heat from the various radiant burners 56 installed in the wall thereof and as before, the design of the burners and the spacing thereof from the tube bank and from each other is so correlated that the heat rays from each burner overlap the heat rays from the next adjacent burner, resulting in the absence of cold spots on the tube bank. In this embodiment also, it is possible to maintain accurate and close zone control of the heating effects on the tube bank. This is accomplished by connecting the various burners in one position of the circumference of the furnace to a single manifold.

45 50 The burners are connected vertically instead of horizontally in this embodiment because the tubes are vertically arranged. If desired, the upper and lower groups of burners in each circumferential section may be supplied by separate manifolds.

55 60 The temperature of the furnace is measured and controlled in response to the internal temperature thereof as measured by thermocouples extending into the furnace through circumferentially and vertically spaced openings 55a in the furnace wall. In this construction also, the furnace temperature in various zones may be controlled by the manual adjustment of individual valves associated with each burner or by manual adjustment of valves similar to valves 55

controlling the supply of gas and air to the burners of each section.

Radiant walls of the type shown in Fig. 5 may be used in the furnaces of Figs. 2 and 3 and Figs. 6 and 7, if desired.

It will of course be understood that any known controls may be used in connection with any of the above modifications in order to obtain completely automatic control of any particular process being followed.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. Apparatus for the continuous heat treatment of fluent substance comprising wall structure of refractory material defining a relatively narrow chamber disposed with its axis in substantially horizontal position, said chamber having an outlet passage at the top thereof and extending substantially throughout its length, a serpentine pre-heating tube portion disposed within said outlet passage and communicating with a serpentine heat treating tube portion disposed lengthwise and centrally within said chamber whereby material treated will flow back and forth in a series of substantially horizontally disposed passes between the upper and lower portions of said chamber, a plurality of burners distributed over the interior of the walls of said chamber on opposite sides of the heat treating portion of said tube and throughout the length and height of the same, the spacing of said burners relative to each other and the spacing of the same relative to said tube being in a manner to provide intimately overlapping radiant heat areas located throughout the length of the heat treating portion of said tube for providing uniform and continuous heat distribution, said burners and contiguous wall portions being constructed and arranged to be heated to incandescence for providing radiant heat, means for selectively controlling the fuel supplied to each burner whereby upon operation of said control means the heat output of the associated burner can be varied for modifying the temperature of the tube portion receiving heat from that burner, the distance of the burners from said tube and spacing of the burners being so correlated that said burners operate at maximum efficiency at any setting of the fuel supply control, and means for selectively admitting air to each burner whereby the portion of the tube normally receiving heat from that burner may be cooled.

2. Apparatus for the continuous heat treatment of fluent substance comprising wall structure of refractory material defining a relatively narrow chamber disposed with its axis in substantially horizontal position, said chamber having an outlet passage at the top thereof and extending substantially throughout its length, a serpentine pre-heating tube portion disposed within said outlet passage and communicating with a serpentine heat treating portion disposed lengthwise and centrally within said chamber whereby material treated will flow back and forth in a series of substantially horizontally disposed paths between the upper and lower portions of said chamber, a plurality of burners distributed in horizontal rows over the interior of the walls of said chamber on opposite sides of said tube and throughout the length and height of said

tube, the spacing of said burners relative to each other and the spacing of said burners relative to said tube being in a manner to provide intimately overlapping radiant heat areas located throughout the length of horizontal sections of said tube for providing uniform and continuous heat distribution of said sections, said burners and contiguous wall portions being constructed and arranged to be heated to incandescence for providing radiant heat, means for selectively controlling the fuel supplied to each row of burners whereby upon operation of said control means the heat output of the associated row of burners can be varied for modifying the temperature of the tube section receiving heat from that row of burners, the distance of the burners from said tube and spacing of the burners being so correlated that maximum efficiency of said burners is obtained with any setting of the fuel supply control.

3. Apparatus for the continuous heat treatment of fluent substance comprising wall structure of refractory material defining a relatively narrow chamber said chamber having an outlet passage at the top thereof and extending substantially throughout its length, a pre-heating tube portion disposed within said outlet passage and communicating with a heat treating portion disposed centrally within said chamber, a plurality of burners distributed over the interior of the walls of said chamber on opposite sides of said tube and throughout the length and height of said tube, the spacing of said burners relative to each other and the spacing thereof relative to said tube being in a manner to provide intimately overlapping radiant heat areas located throughout the length of said tube for providing uniform and continuous heat distribution, said burners and the contiguous wall portions being constructed and arranged to be heated to incandescence for providing radiant heat, means for selectively controlling the fuel supplied to each burner whereby upon operation of said control means the heat output of the associated burner can be varied for modifying the temperature of the tube portion receiving heat from that burner, the distance of the burners from said tube and the spacing of said burners being so correlated that maximum efficiency of said burners is obtained with any setting of the fuel supply control, and means for selectively admitting air to each burner whereby the portion of the tube normally receiving heat from that burner may be cooled.

4. Apparatus for the continuous heat treatment of fluent substance comprising wall structure of refractory material defining a relatively narrow chamber disposed with its axis in a substantially horizontal position, said chamber having an outlet passage at the top thereof and extending substantially throughout its length, a serpentine pre-heating tube portion disposed within said outlet passage and communicating with a serpentine heat treating portion disposed lengthwise and centrally within said chamber whereby material treated will flow back and forth in a series of substantially horizontally disposed paths between the upper and lower portions of said chamber, a plurality of burners distributed over the interior of the walls of said chamber on opposite sides of said tube and throughout the length and height of said tube, the spacing of said burners relative to each other and the spacing thereof relative to said tube being in a manner to provide intimately overlapping radiant heat areas located throughout the length of said

tube for providing uniform and continuous heat distribution, means for selectively controlling the fuel supplied to each burner whereby upon operation of said control means the heat output of the associated burner can be varied for modifying the temperature of the tube portion receiving heat from that burner, and means for selectively admitting air to each burner whereby the portion of the tube normally receiving heat from that burner may be cooled.

5. Apparatus for the continuous heat treatment of fluent substance comprising wall structure of refractory material defining a relatively narrow chamber, a serpentine tube disposed centrally within said chamber whereby material treated will flow back and forth in a series of substantially horizontally disposed paths between the upper and lower portions of said chamber, a plurality of burners distributed over the interior of the walls of said chamber on opposite sides of said tube and throughout the length and height of said tube, the spacing of said burners relative to each other and the spacing thereof relative to said tube being in a manner to provide intimately overlapping radiant heat areas located throughout the length of said tube for providing uniform and continuous heat distribution, means for selectively controlling the fuel supplied to each burner whereby upon operation of said control means the heat output of the associated burner can be varied for modifying the temperature of the tube portion receiving heat from that burner, and means for selectively admitting air to each burner whereby the portion of the tube normally receiving heat from that burner may be cooled.

6. Apparatus for the continuous heat treatment of fluent substance flowing in a confined path comprising wall structure of refractory material defining a relatively narrow chamber, a horizontally disposed serpentine tube disposed centrally within said chamber whereby material treated will flow back and forth in a series of substantially horizontally disposed passes between the upper and lower portions of said chamber, a plurality of horizontal rows of burners distributed over the interior of the walls of said chamber on opposite sides of said tube, the spacing of said burners relative to each other and the spacing thereof relative to said tube being in a manner to provide intimately overlapping radiant heat areas located throughout the length of said tube for providing uniform and continuous heat distribution, means for selectively controlling the fuel supplied to each row of burner whereby upon operation of said control means the heat output of the associated burners can be varied for modifying the temperature of the tube portion receiving heat from that burner.

7. Apparatus for the continuous heat treatment of fluent substance comprising wall structure of refractory material defining a relatively narrow chamber, a serpentine tube disposed centrally within said chamber whereby material treated will flow back and forth in a series of passes between the walls of said chamber, a plurality of rows of radiant burners extending in the direction of said passes over the interior of the walls of said chamber on opposite sides of said tube and throughout the extent of said tube, the spacing of said burners relative to each other and the spacing thereof relative to said tube being in a manner to provide intimately overlapping

radiant heat areas located throughout the length of said passes for providing uniform and continuous heat distribution along said passes, means for selectively controlling the fuel supplied to each burner whereby upon operation of said control means the heat output of the associated burner can be varied for modifying the temperature of the pass receiving heat from that burner.

8. Apparatus for the continuous heat treatment of fluent substance flowing in a confined path comprising wall structure of refractory material defining a relatively narrow chamber, a horizontal serpentine tube disposed centrally within said chamber whereby material treated will flow back and forth in a series of substantially horizontally disposed paths between the upper and lower portions of said chamber, a plurality of radiant heat sources distributed in horizontal rows over the interior of the walls of said chamber on opposite sides of said tube and throughout the length and height of said tube, the spacing of said sources relative to each other and the spacing thereof relative to said tube being in a manner to provide intimately overlapping radiant heat areas located throughout horizontal portions of the length of said tube for providing uniform and continuous heat distribution along said portions and, means for selectively controlling the heat output of each of said radiant heat sources whereby upon operation of said control means the heat output of the associated radiant heat source can be varied for modifying the temperature of the tube portion receiving heat from that source.

35. 9. Apparatus for the continuous heat treatment of fluent substance flowing in a confined path comprising wall structure of refractory material defining a chamber, a serpentine tube disposed within said chamber whereby material treated will flow back and forth in a series of substantially horizontally disposed passes between the upper and lower portions of said chamber, a plurality of burners disposed in said wall structure, the configuration of said burners and the spacing thereof relative to said tube being in a manner to provide intimate overlapping radiant heat areas for providing uniform and continuous heat distribution in the region of said tube, means for selectively controlling the fuel supplied to each burner whereby upon operation of said control means the heat output of the associated burners can be varied for modifying the temperature of the tube portion receiving heat from that burner, and means for selectively admitting air to each burner whereby the portion of the tube normally receiving heat from that burner may be cooled.
